(57) **CLAIM**

The ornamental design for a lighted cable termination assembly, as shown and described.

DESCRIPTION

FIG. 1 is an isometric view of a front, top, and left side of an embodiment of a lighted cable termination assembly; FIG. 2 is a left side elevational view of the lighted cable termination assembly of FIG. 1; FIG. 3 is a right side elevational view of the lighted cable termination assembly of FIG. 1; FIG. 4 is a front elevational view of the lighted cable termination of FIG. 1; FIG. 5 is a rear elevational view of the lighted cable termination assembly of FIG. 1; FIG. 6 is a top plan view of the lighted cable termination assembly of FIG. 1; FIG. 7 is a bottom plan view of the lighted cable termination assembly of FIG. 1; FIG. 8 is an isometric view of a front, top, and left side of a different embodiment of a lighted cable termination assembly;

FIG. 9 is a left side elevational view of the lighted cable termination assembly of FIG. 8; FIG. 10 is a right side elevational view of the lighted cable termination assembly of FIG. 8;

FIG. 11 is a front elevational view of the lighted cable termination assembly of FIG. 8; FIG. 12 is a rear elevational view of the lighted cable termination assembly of FIG. 8;

FIG. 13 is a top plan view of the lighted cable termination assembly of FIG. 8; and,

(Continued)

FIG. 14 is a bottom plan view of the lighted cable termination assembly of FIG. 8.
The broken lines showing a portion of the lighted cable termination assembly form no part of the claimed design.

1 Claim, 10 Drawing Sheets
